United States Patent Office.

WILLIAM HENRY BURNS, OF GRAFTON, ASSIGNOR TO JONATHAN LUTHER, OF WORCESTER, MASSACHUSETTS.

Letters Patent No. 95,314, dated September 28, 1869.

IMPROVEMENT IN ROLLER JAW-TEMPLE FOR LOOMS.

The Schedule referred to in these Letters Patent and making part of the same.

To all whom it may concern:

Be it known that I, WILLIAM HENRY BURNS, of Grafton, county of Worcester, Commonwealth of Massachusetts, have invented a new and improved Roller Jaw-Temple for Looms; and I do hereby declare that the following is a full and exact description thereof, reference being had to the accompanying drawings, and to the letters of reference marked thereon, making a part of this specification.

The nature of my invention consists in constructing a roller jaw-temple, with concave grooves in the rolls for holding, sustaining, and extending the cloth as it passes over the breast-beam of the loom, hereinafter more fully described.

It is simple in its construction, and easily adjusted for any thickness of cloth; can be applied to all looms for weaving cloth. It will hold the cloth evenly, and does not tear or deface the edges of the cloth.

In the drawings—

Figure 1 represents a perspective view of my roller jaw-temple. Screw *h* fastens the upper and lower jaws together. Screw *s* adjusts the jaws to any thickness of cloth required. The slots *I* are for bolting the temple to its position on the spring, which is on the breast-beam of the loom.

Figure 2 represents the lower jaw, with the roller *D* in its place; also, the raised lip *G*, which has teeth, into which the upper roll *C* matches when adjusted, as seen in fig. 1.

Figure 3 represents a sectional view of the upper and lower jaws *A* and *B*, the rollers *C* and *D*, with concave grooves, and the arbors *E* and *F*.

To enable others skilled in the art to make and use my invention, I will proceed to describe its construction and operation.

I make the upper and lower jaws of cast-iron or other metals.

My rollers, as seen in fig. 3, are turned with concave grooves. These rollers run to match into each other. The roller *D*, in the lower jaw, is placed on an angle of one-eighth of an inch, more or less, which serves to incline the edges of the cloth outward.

Concave teeth are made in the lip *G* of the lower jaw, which fit into the concave grooves of the upper roll *C*, as seen in fig. 1, when brought together by means of the screws *s* *h*.

By this arrangement the cloth, when drawn through between the upper roll and the teeth, and then between the two grooved rollers, is held securely, and, as the rolls revolve on the arbors, the edges of the cloth are constantly working outward, and the cloth is thus held suspended as it is being woven.

The angle at which I place the roll, causes it to operate on the cloth in its revolution something like a screw.

The roller *D* is mounted on its journal *F*, so that it may move laterally thereon, and toward the centre of, and over the surface of the cloth, when the lay beats up and slackens the cloth; but when the web is drawn taut, the rollers are drawn together, and the roller *D* slides outward and stretches the cloth widthwise.

I am aware that roller-temples have been made with teeth and spurs in various ways; but

What I claim, and desire to secure by Letters Patent, as my invention, is viz:

The combination with the jaws *A* *B* of the grooved rollers *C* *D*, the latter arranged to reciprocate laterally on its journal, and toothed-lip *G* of the jaw *B*, when constructed as and for the purpose described.

WM. HENRY BURNS.
